(57) **CLAIM**

The ornamental design for an intraocular lens implantation device, as shown and described.

DESCRIPTION

FIG. 1 is a front view of an intraocular lens implantation device showing our new design;

FIG. 2 is a rear view thereof;

FIG. 3 is a left side view thereof;

FIG. 4 is a right side view thereof;

FIG. 5 is a top plan view thereof;

FIG. 6 is a bottom view thereof;

FIG. 7 is a top perspective view thereof; and,

FIG. 8 is a bottom perspective view thereof.

The dot-dot broken lines are directed to illustrative environmental subject matter that forms no part of the claimed design or to portions of the devices that form no part of the claimed design. The dash-dot broken lines represent bounds of the claimed design and do not themselves form a part of the claimed design.
